UNITED STATES PATENT OFFICE.

VICTOR ODQUIST AND HALVOR HEYERDAHL LYCHE, OF CHICAGO, ILLINOIS; SAID ODQUIST
ASSIGNOR TO TORRIS WOLD & COMPANY, OF CHICAGO, ILLINOIS, A CORPORATION OF
ILLINOIS.

CAN-BODY-FLANGING MACHINE.

No. 900,119.

Specification of Letters Patent.

Patented Oct. 6, 1908.

Application filed December 4, 1906. Serial No. 346,282.

To all whom it may concern:

Be it known that we, VICTOR ODQUIST and HALVOR HEYERDAHL LYCHE, both citizens of the United States, and both residents of Chicago, in the county of Cook and State of Illinois, have invented a certain new, useful, and Improved Can - Body - Flanging Machine, of which the following is a full, clear, and exact description, such as will enable others skilled in the art to which it appertains to make and use the same.

Our invention relates to can making machines, and has particular reference to machines for flanging can non-circular bodies preparatory to seaming the ends or heads thereon.

In order to seam the heads upon can bodies both the heads and the bodies must be flanged, previous to the process of seaming; and the function of the machine is to form the necessary flange upon the can body.

The object of our invention is to provide a simple, compact, and durable machine for flanging can bodies, and one which will rapidly and efficiently flange both ends of a can body simultaneously.

Another object of our invention is to provide a machine of the class mentioned which shall be capable of flanging can bodies of any shape or size.

A further object of our invention is to provide a machine of this class, which will operate with great exactness to form flanges of equal or predetermined width upon can bodies; and one which when set in operation will automatically complete the flanging of the can body and then stop preparatory to the removal of the can body and the insertion of another.

Other objects of our invention will appear hereinafter.

Our invention consists generally in a non-rotative can body holding chuck, a flanging roller adapted to revolve about the inner face of the can body, and suitable mechanism for throwing said roller into and out of operation upon said can body. Further, our invention consists in a main mechanism for flanging can bodies, and suitable interchangeable attachments for said mechanism, which attachments shall adapt said mechanism for flanging can bodies of various shapes and sizes.

Our invention further consists in various novel constructions and arrangements of

parts, all as will be hereinafter fully described and particularly set forth in the claims.

Our invention will be more readily understood by reference to the accompanying drawings, and in which—

Figure I is a side elevation of a machine embodying our invention, parts being broken away for the sake of greater clearness; Fig. II is a bottom plan view on an enlarged scale of the flanging roller carrying mechanism, the operating cam being omitted to better illustrate the remaining parts; Fig. III is a vertical section on the line III—III of Fig. II; Fig. IV is a similar view on the line IV—IV of Fig. II; Fig. V is a cross section of the roller carrying slide on the line V—V of Fig. IV; Fig. VI is a bottom plan view similar to Fig. II, on a slightly decreased scale, showing the roller operating cam in place; Fig. VII is a detail plan view of a portion of the operating mechanism; Fig. VIII is a plan view of a can body holding chuck such as is used in flanging oval can bodies; Fig. IX is an elevation of the chuck illustrated in Fig. VIII looking in the direction of the arrow "a"; Fig. X is a section on the line X—X of Fig. VIII, illustrating the chuck in its lowermost position, and a can body in position to be flanged, the same being shown in dotted lines; Fig. XI is a view similar to Fig. X, illustrating the chuck in its raised position; and Fig. XII is a detail illustrating the coaction of the roller and chuck in flanging a can body.

In order that our invention may be more readily understood, a brief description of the machine will be given as a whole, before describing the same in detail; it being understood that no attempt will be made therein to particularize, the idea being merely to present the machine as a unit, to the end that its *modus operandi* may be grasped at once.

The operating mechanisms, including means for starting and stopping the machine, are mounted upon a suitable frame and suitable brackets attached thereto. A flanging roller is rotatably supported from a bracket overhanging the frame, and means are provided for giving the same several orbital revolutions, after having been started, and automatically operative means for stopping said roller when it has made the required revolutions. A non-circular can-

body holding chuck is located beneath the flanging roller and suitable means are provided for imparting vertical reciprocation thereto at the proper times. This comprises a foot actuated lever and suitable connections therebetween. The same lever is also used to start the machine, by throwing in a clutch;—connecting the constantly rotating drive shaft with the operating mechanisms.

- 10 A can body is first placed in the chuck, with its edges somewhat above and below the upper and lower edges of the body portion of the chuck. Then the operator raises the chuck and can-body by means of the foot lever. By this operation the flanging roller is placed within the can-body and the clutch is thrown in to start the machine. Suitable mechanism then automatically throws the roller outwardly and rotates it orbitally 15 against the can body and the flanges provided thereon at both top and bottom bend the edges of the can body over the edges of the chuck, forming the required flange. The roller is kept in operative relation with the chuck and can body until it makes one or more complete circuits thereof, after which it is automatically retracted, and the machine stopped.

1 indicates the frame of the machine, and 20 2, 3, 4, and 4', brackets which support the operating mechanisms thereon. The main drive shaft 5 extends from bearings in the bracket 2 to bearings in the bracket 4, and is provided with a fast and a loose pulley, 6 25 and 7. A belt shifter 8 extends to the forward part of the machine, where it is within easy reach of the operator. A sleeve 9, equipped with a worm 10, is loosely mounted upon the drive shaft 5, and is coupled there- 30 with by a clutch device 11. The clutch 11 is operated by a foot lever 12, and in the following manner. A lever 13, carrying a pin 14, is connected to the lever 12 by a rod 15. As the foot lever 12 is depressed, the lever 40 13 is also depressed, and the pin 14, carried thereby, engages the end of a lever 16, pivoted in the bracket 3, and operates the same to throw the clutch 11. A latch 17 engages the pin 14, and keeps the clutch in operation 45 until the machine has operated to flange a can body, when it is automatically tripped to stop the machine, as will be described later.

50 A worm wheel 20 is mounted upon the bracket 4', and engages the worm 10. Attached to the worm wheel 20 and concentrically mounted therewith on the bracket 4', is a cam 21, which operates a lever 22, to throw the flanging roller into and out of operation, in a manner described hereinafter. 55 Upon the bottom of the cam 21 is a lug 24, which, when the machine is at a standstill, depresses a lever 25 upon the end of a shaft 26. This is the shaft to which the latch 17 is attached, and consequently, when the lug 60 24 engages the lever 25 the latch is held out

of engagement with the pin 14, and the lever 13 is permitted to rise. When the machine is started the foot is kept on the lever 12 until the lug 24 passes beyond the lever 25, allowing the latch to engage the pin 14. Then 70 the foot may be removed and the machine will continue its operation until the cam 21 has made one revolution, when the lug 24 again trips the latch as described. A spring 27 returns the levers 12 and 13 to normal position, and in doing so, the end of the rod 15 operates the lever 16 to shift the clutch 11, thereby stopping the machine. The end of the lever 13 actuates a brake shoe 28, which, by engaging the loose portion of the clutch, 75 insures the stopping of the machine at the proper time. This is withdrawn from operative position when the lever 13 is depressed to start the machine.

The chuck comprises a non-circular clamp 85 in which the irregularly shaped can body is held during the process of flanging, a plate upon which the clamp is supported, a gage for positioning the can bodies in the clamp, and a latch for keeping the clamp closed.

80 The clamp consists of a stationary portion 30, fastened securely to a plate 31, and a portion 32, hinged as at 33 to the part 30. The parts 30, 32, are so shaped as to fit snugly, when closed, about the can body and grip it 95 when closed thereon. A separate chuck is provided for each size and shape of can to be flanged upon the machine. The hinged part 32 has a handle 34, to facilitate opening and closing the chuck clamp, and a latch 35. 100 serves to hold the clamp tightly closed while the machine is in operation. The plate 31 is recessed as at 36, and the clamp members are so arranged as to slightly overhang the edges thereof, as shown in Figs. X and XI. 105 This is to permit the lower edge of the can body to be bent thereunder. See Fig. XII. The chuck is supported upon a vertically reciprocative shaft 38, mounted in a bracket 39, adjustably secured to the front of the 110 frame 1. The shaft 38, and the chuck, are operated by the lever 12. A chain or other flexible member 40 is attached to an adjustable collar 38' upon the shaft 38, and passes over a roller 41, mounted upon the bracket 115 39, or if desired upon the frame 1. The flexible member 40 is attached to the lever 12 through a turn-buckle 42 and spring 43. The collar 38' limits the upward movement of the chuck by abutting the end of the 120 guide or sleeve of the bracket 39. When cans of greater or less height are flanged, it is evident that the bracket 39 must be lowered or raised. The turn-buckle 42 affords ample adjustment for the lifting device, and the spring 43 a lost motion to permit further depression of the lever 12 after the up-stroke of the chuck has been arrested by the collar 38'.

125 The can body before flanging is of greater 130

height than the clamp of the chuck, and the excess extends equally above and below said clamp. This is the portion which is bent over the edges of the clamp to form the flanges, and as the flanges must be of certain and uniform size, the can bodies must be placed in the clamp with great exactness. This would present no difficulty if the bottom of the recess 36 could be utilized to 10 gage the position of the can body in the clamp. But this is impracticable as the space between the bottom edge of the clamp and the bottom of the recess would not be sufficient to accommodate the flange of the 15 flanging roller. Hence a gage must be provided to insure accuracy and a uniformity in the flanges formed. To this end the chuck is provided with a false bottom and means for raising and depressing the same 20 at the proper times. 45 indicates the false bottom. This comprises a plate coextensive in area with the recess 36 and contained therein. Two rods or posts 46 are attached to the bottom thereof and extend through 25 the bottom of the recess 36. When the chuck is down, ready to insert a can body, the rods 46 rest upon adjusting screws 48 in the bracket 39, which elevates the plate 45. The exact position of the plate at this time can 30 be determined by the screws 48. When the chuck is raised, the plate drops to the bottom of the recess, giving ample room for the flanging roller. The clamp holds the can body securely enough to prevent the same 35 from dropping with the plate 45.

The flanging roller consists of a cylinder 50, provided with an annular flange or rib 51 at each end. The distance between the ribs 51 is slightly greater than the height 40 of the clamping members 30-32, so that as the roller is pressed outwardly against the can body and the clamp, the edges of the can body are turned outwardly to form the flanges, as shown in Fig. XII, in which 53 indicates the can body.

As before stated the can body is held against rotation, and the flanging roller revolves about the inner face thereof. Further, the roller is automatically thrown into 50 and out of engagement with said can body at the proper times, and further, means are provided for maintaining the roller in contact with the can, throughout the flanging operation, whatever the shape of the can 55 may be. To these ends the roller is mounted upon a suitable lever, which is in turn pivotally and slidably mounted upon a rotary member located above and on an axis concentric with that of the chuck; and suitable 60 means are employed for moving said lever radially upon said rotating member, and for causing the roller thereon to travel a path parallel with the periphery of the can body.

65 The rotating member comprises a wheel

55, mounted upon a shaft 56, depending from the overhanging bracket 4. Rotation is imparted to the wheel by a belt 55', which connects it with a pulley 5' upon the main drive shaft 5.

The wheel 55 is provided with two broad radially disposed spokes 56, 57, and two smaller ones 58. The spokes 56, 57, are slotted and carry respectively, slides 59, 60. These move in the same straight line and 75 are connected by yokes 61, hence move together as a unit.

The slides are channeled as shown, and the bottom of the slide 59 is slotted as at 62. A screw 63, passing through the slot 62, and 80 into a block 64, adjustably secures the latter to the slide. It is to the block 64 that the lever which carries the flanging roller is pivoted.

65 indicates the lever. This comprises an 85 upper pivot portion 66, an offset portion 67, and a lower, roller carrying portion 68. It is pivoted to the block 64 by a stud 70 and screw 71. The lower, roller carrying portion 90 68 of the lever 65 is substantially triangular in form; the offset portion 67 being at an angle, the flanging roller 50 depending from another, and a roller 72 extending upwardly from the third.

It will be noted that by adjusting the block 95 64 upon the slide 59, the roller 50 may be moved toward or away from the center of the wheel 55, according to the size of the can bodies to be flanged.

The roller 72 engages a cam groove 73, in 100 the under face of a disk 74. The disk 74 is secured to the lower end of the shaft 56 by a screw or other suitable means, and is keyed thereto to prevent rotation. The cam groove 73 is of such shape, as to cause the roller 50 105 to travel in a path parallel with the periphery of the can when the wheel 55 is rotated.

To throw the roller 50 into and out of engagement with the can body and chuck, recourse is had to the following means. A 110 lever 75 is pivoted above the slide 60, to a collar 76 which rotates with the wheel 55. At its upper end it is provided with a nose 77, and its lower end is bifurcated, as at 78, to engage a pin 79, extending across the 115 groove in the slide 60. A cam 80 is slidably mounted upon the shaft 56 between the wheel 55 and the bracket 4. This is operated by the aforementioned cam 21, through the lever 22. As the cam 21 rotates, the cam 80 is 120 moved downwardly, engaging the nose of the lever 75 and rocking said lever, as shown in Fig. III. This moves the slide 60 inwardly, and as said slide is rigidly connected to slide 59, the latter is moved outwardly, 125 carrying therewith the roller 50. After the can body is flanged, the cam 21 raises the cam 80 and a pair of springs 81 return the slides to normal position, throwing the roller 50 out of action.

To regulate the pressure of the roller 50, means are provided for adjusting the distance between the slides 59 and 60. Accordingly the yoke members 61 are attached to 5 the slide 60 by an eccentric pin 85, and the end of the pin is kerfed, as at 86, to receive a suitable tool such as a screwdriver. By turning the pin 85 the distance between the slides may be nicely adjusted. A clamp 87 10 secures the pin against turning after having been set, and hence maintains the proper distance between the slides.

The operation of the machine is as follows: Assuming that the machine is at rest except 15 that the belt is running on the fast pulley, the operator places a can body in the chuck and closes the clamp thereupon. The chuck being at its lowest position at this time, the false bottom is raised, so that when the can 20 body is placed therein it rests upon said false bottom. When the clamping members are closed and latched the can body is held snugly between them. He then depresses the lever 12 with his foot. This raises the chuck into 25 position for coöperation with the roller 50, and also starts the machine in operation by throwing in the clutch in the manner hereinbefore described. As soon as the clutch is thrown in the worm and worm wheel begin 30 to rotate, the latter carrying with it the cam 21. When the lug 24 on the bottom of the cam 21 has traveled a short distance, or out of engagement with the lever 25, it permits the latch 17 to engage the pin on the lever 13. 35 This holds the clutch in operative position until the cam 21 makes a complete revolution, at which time the lug 24 again trips the latch 17, releasing the clutch as described. As soon as the cam 21 starts to rotate, it lowers 40 the cam 80, on the shaft 56, thereby throwing the roller 50 into operative position to flange the can body. The wheel 55 is constantly rotating and carries with it the roller 50, so that when the roller is pressed against the 45 can body it quickly makes several complete revolutions within it, turning both the top and bottom edges of the can body outwardly over the clamping members of the chuck, forming neatly and accurately, the desired 50 flanges. The cam 80 is held in its lowermost position during the entire time the can is being flanged, and rises again just previous to the time when the lug 24 operates to stop the machine. As soon as the clutch 11 is thrown 55 out the brake shoe 28 impinges against a part on the worm sleeve and insures instantaneous stopping of the worm and cam, and unlatching the treadle, lowers the chuck.

Having thus described our invention, we 60 claim as new and desire to secure by Letters Patent:

1. In a machine of the class described, an irregular non-rotatable can body holder comprising a clamp of less height than 65 that of the can body to be flanged, in combi-

nation with a roller provided with annular flanges or collars separated by a space greater than the height of the clamp, and means for revolving said roller within said holder, substantially as described.

70

2. In a machine of the class described, the combination of a can body holder with an automatically operating gage for positioning a can body therein, means for adjusting said gage, a flanging device, and means for moving said flanging device into operative position within a can body held in said holder to form flanges on said can body, substantially as described.

75

3. In a machine of the class described, a can body holder comprising a two-part clamp of less height than that of the can body to be flanged, in combination with a plate arranged beneath said clamp, means for adjusting said plate in relation to said clamp, a flanging device, and means for actuating said flanging device within a can held in said clamp to flange the can body, substantially as described.

80

4. In a machine of the class described, a can body holder comprising a clamp, in combination with a plate beneath said can body holder, means for automatically moving said plate toward and away from said can body holder, a flanging device, and means for moving said flanging device into coöperation with said clamp to flange a can body, substantially as described.

90

5. In a machine of the class described, a can body holder comprising a clamp of less height than that of the can body to be flanged, in combination with a plate beneath said clamp for gaging a can body therein, a flanging roller of greater height than the can body, means for inserting said roller within said can body and clamp, means for depressing said plate out of the path of said roller, and means for moving said roller into coöperation with said clamp to flange the can body, substantially as described.

100

6. In a machine of the class described, a can body holder comprising a clamp of less height than that of the can body to be flanged, in combination with a plate beneath said clamp, a flanging device arranged above said can body holder, means for raising said can body holder to insert said flanging device therein and for depressing said plate in relation thereto, and means for operating said flanging device, substantially as described.

105

7. In a machine of the class described, a wheel, in combination with a pair of slides radially mounted upon said wheel, means connecting said slides, a flanging roller upon one of said slides, means for radially moving the other slide to shift said flanging roller into and out of operation, and a can body holding device concentric with said wheel, substantially as described.

125

130

8. In a machine of the class described, a wheel, in combination with a pair of slides radially mounted on said wheel, an adjustable connection between said slides, a flanging roller upon one of said slides, means for radially moving the other slide to shift said flanging roller into and out of operation, and a can body holding device concentric with said wheel, substantially as described.
9. In a machine of the class described, a can body holder comprising a clamp of less height than that of the can body to be flanged, in combination with a plate beneath said clamp, a flanging device arranged above said can body holder to insert said flanging device therein and to depress said plate in relation thereto, means for operating said flanging device, and a cam for causing the roller to follow the periphery of the can, substantially as described.
10. In a machine of the class described, a can body holding device, in combination with a wheel concentric therewith, a pair of slides upon said wheel, a yoke pivotally connected to one of said slides, an eccentric pin connecting said yoke with the other slide, a flanging device mounted upon one of said slides, and means for radially moving the other slide into and out of operative position, substantially as described.
11. In a machine of the class described, a can body holding device, in combination

with a wheel arranged concentric therewith, a pair of slides upon said wheel, a yoke pivotally connected to one of said slides, an eccentric pin connecting said yoke with the other slide, a flanging roller mounted upon one of said slides, means for operative connection with the other slide adapted to automatically shift said flanging roller into and out of operation, and means for automatically stopping the mechanism when said roller has completed its operation, substantially as described.

12. In a machine of the class described, a wheel, in combination with a flanging device upon said wheel, means for rotating said wheel, an irregular can body holding device, means for inserting said flanging device within said holder, means for automatically moving said flanging device into and out of operative relation thereto, and a cam for causing the flanging device to follow the periphery of a can to form flanges thereon, substantially as described.

In testimony whereof, we have hereunto set our hands, this 22nd day of November, 1906, in the presence of two subscribing witnesses.

VICTOR ODQUIST.
